COMBINED RADIO CABINET AND TOILET PAPER HOLDER

John F. Louis, 11962 York Ave.,
Hawthorne, Calif. 90250

Filed Oct. 22, 1968, Ser. No. 14,112

Term of patent 14 years

Int. Cl. D6—01

U.S. Cl. D33—31

Fig. 2

FIG. 1 is a perspective view of a combined radio cabinet and toilet paper holder, showing my new design.

FIG. 2 is a sectional view taken on line 2—2 of FIG. 1.

The broken line representation of radio knobs in FIG. 1 and the knobs and their connecting shafts in FIG. 2 are for purposes of illustration only.

I claim:

The ornamental design for a combined radio cabinet and toilet paper holder, substantially as shown and described.
